CLAIM

The ornamental design for a combined fly tying bobbin holder and thread guide, substantially as shown and described.

DESCRIPTION

FIG. 1 is a front perspective view of a combined fly tying bobbin holder and thread guide showing my new design;

FIG. 2 is a front elevational view, the rear view being identical thereto;

FIG. 3 is a right side elevational view, the left side being identical thereto;

FIG. 4 is a top plan view thereof; and

FIG. 5 is a bottom plan view thereof.

FIG. 1

FIG. 2

FIG. 3

FIG. 4

FIG. 5
